US00D475622S

(12) **United States Design Patent** (10) Patent No.: **US D475,622 S**
(45) Date of Patent: **** Jun. 10, 2003**

(54) **SNACK FOOD CONTAINER**

(75) Inventor: **Joseph Paul Sagel**, Highland Village, TX (US)

(73) Assignee: **RECOT, Inc.**, Pleasanton, CA (US)

(**) Term: **14 Years**

(21) Appl. No.: **29/155,284**

(22) Filed: **Feb. 11, 2002**

(51) LOC (7) Cl. **09-03**

(52) U.S. Cl. **D9/429; D9/428**

(58) Field of Search D9/418, 414, 428, D9/429, 425, 424, 430, 432, 500, 502, 503, 504, 513, 549, 573, 520-543, 552-560; 229/400-405, 406, 109, 110, 911; 220/241, 242, 288, 290, 781, 350, 351, 376, 380, 602, 625, 635, 636, 669, 675, 906; 206/508, 303, 446; 215/2, 6, 370, 376, 377, 381-384; 222/92, 107, 105

(74) Attorney, Agent, or Firm—Colin P. Cahoon; Carstens, Yee & Cahoon, L.L.P.

(57) **CLAIM**

The ornamental design for a snack food container, as shown and described.

DESCRIPTION

FIG. 1 is a perspective view of the snack food container of the present invention;

FIG. 2 is a top perspective view of the snack food container of the present invention;

FIG. 3 is a front elevation view of the snack food container of the present invention, with the rear elevation view a mirror image of the front elevation view;

FIG. 4 is a right elevation view of the snack food container of the present invention, with the left elevation view a mirror image of the right elevation view;

FIG. 5 is a top plan view of the snack food container of the present invention; and,

FIG. 6 is a bottom plan view of the snack food container of the present invention.

The broken lines defining a center portion of the snack food container, as shown in FIGS. 1, 2, 3, and 4, are for illustrative purposes only and form no part of the claimed design.

1 Claim, 3 Drawing Sheets
